VEHICLE DOOR LOCK

Glen A. Smith, Detroit, Mich., assignor to General Motors Corporation, Detroit, Mich., a corporation of Delaware

Application December 8, 1945, Serial No. 633,671

17 Claims. (Cl. 292—5)

1

A lock for automobile doors is the subject of this application.

Among the objects and advantages of the new lock are the following:

The door is held by the engagement of a latch and cam one of which is in the post and the other in the door. In closing the door with the door latch held by a trigger, the post cam swings against the resistance of a spring. To open the door the trigger must be disengaged from the door latch. This is effected from the outside by a handle or from the inside by a push button.

The known vertically reciprocable push rod may be used not only to lock the mechanism from outside release but also from inside release.

The outside control is in the form of a straight pull handle wherein the part grasped by the hand remains parallel with the side of the body.

A spring loaded cam action avoids the necessity of slamming the door. The door can be closed from "safety" position without reopening. There is included a rugged dependable safety catch acting independently of the latching device.

Other objects and advantages will be understood from the description which follows.

An embodiment of the invention is shown on the accompanying drawing wherein—

Fig. 1 is a view from within, showing in elevation a vehicle door, with parts broken away to illustrate door operating mechanism.

Fig. 2 is a section on line 2—2 of Fig. 1.

Fig. 3 is a vertical section through the door.

Fig. 4 is a section on line 4—4 of Fig. 3.

Fig. 5 is a section on line 5—5 of Fig. 3.

Fig. 6 is a horizontal section through the door and its post.

Fig. 7 is a section on line 7—7 of Fig. 6.

Fig. 8 is a vertical section through that part of the locking mechanism carried by the door with parts displaced from the positions shown by Fig. 7.

Fig. 9 is a view like Fig. 8 with a different placement of parts.

Referring by reference characters to the drawing, numeral 11 represents a door. The door post is marked 13. Within the post adjacent the door in the closed position of the latter is secured a housing 17 having an upper region 19, a lower region 21, the upper and lower regions having between them a relatively large region 23 into which moves a door carried casing 25. In the upper region is pivoted at 27 a keeper means in the form of a locking cam 29 biased by a heavy spring 31 to the position shown by Fig. 7 where its angular end projects into the region 23 and its extreme end is stopped by the wall separating the upper and

2

middle regions. Provision is made for adjusting the cam carrying member as seen at 15. Within the lower region a wedge block 33 is pressed by a spring 35. The block extends into the middle region where it engages the door carried casing 25 and urges it upwardly so that it contacts the wall of housing 17 in door closed position. This provision avoids the need for conventional dovetail engaging parts.

10 The door carried casing 25 has pivoted therein at 37 a latch 39. Latch 39 has an upper face 41 adapted to engage face 43 of cam 29 as the door closes. If latch 39 is held from rotation in a manner to be explained cam 29 swings up against the tension of spring 31 and the parts assume the position shown by Fig. 7 in which the door is held closed. The door is opened by releasing a trigger 45 which has a face 47 adapted to engage an undercut face 49 on latch 39 as shown in Fig. 7 and in Fig. 9. A spring 51 is supported on the hub 53 of the trigger and has an end which engages latch 39 as shown at 55. This spring is relatively light and if the trigger be withdrawn from contact with latch 39 the door may be 20 opened, the latch swinging at its end rides over cam 29.

The trigger may be swung to its release position from within the vehicle or from without if the door is not locked. Figs. 1 and 2 show a push button 57 in the inner face of the door. When pushed, it operates through the instrumentality of a pin 59 and an arm 61 to rotate a rod or rockshaft 63 against a restoring spring 65. The shaft extends across the door and is journalled at its ends. Adjacent the end remote from the push button it has an arm 67. Arm 67 engages a crank 69 of a crankshaft 71 rotatably supported in the door casing. The operating end of shaft 71 is squared into an opening of the hub of the trigger as shown at 73. Normally 30 when the button is pushed the trigger may be rotated to the position shown by Fig. 8 and the door may be opened.

To release the locking trigger from outside 45 the door one pulls the U-shaped handle 75. The arms of the handle slide in the door. Within the door are two overlapping levers 77 and 79 terminally pivoted to the door at 81 and 83 respectively. At their mid points the levers are pinned together at 85, and a spring 87 associated with the pin biases the levers and the door handle to the full line position shown in Fig. 6. The opposite ends of the levers are connected to the handle arms at 89 and 91. The levers 77 and 79 50 are preferably slotted at the pivots 89 and 83.

Lever 79 is extended and its extreme end is forked as at 93 to engage a lever 95 pivoted in the door at 97. Lever 95 has an arm 99 deflected to enter a recess 101 in a sliding plate member 103. This plate member 103 constitutes control means for trigger 45 for holding the latch 39 in door locking position and for releasing said latch. Plate member 103 has a slot 105 to accommodate a casing pin 107 and permit it to slide and rock or rotate. The plate 103 has an arm 109 adapted to engage a shoulder 111 on the trigger so that as the plate slides in response to handle movement the trigger is released and a spring 113 is stressed and is available to restore the parts to the position shown by Fig. 7.

There is provided on the inside of the door a reciprocable rod 115 which, when moved downward, prevents the opening of the door by the handle 75, the sliding plate 103 and the trigger. Rod 115 is connected to a rod extension 117 suitably guided in the door. The lower end of rod extension 117 is connected to a lever 119 which may be rocked on its pivot 121 by depressing rods 115, 117 as shown in Fig. 5. A flat spring 120, biased in the direction of pivot 121, having one end connected to the lever 119 at 120a and the other end anchored to bracket 120b acts to hold lever 119 and consequently rod 115 and rod extension 117 in either of the adjusted positions shown in Fig. 5. In the full line position the point of attachment 120a of spring 120 is below the pivot 121 of lever 119 and in the dotted line position shown in Fig. 5 the point of attachment has moved above said pivot 121. Thus in the positions of rest of lever 119 the attachment point 120a is either below or above the pivot 121. Pin 122 on plate 103 extends into the end of this lever so that when the lever is rocked to the dotted line position of Fig. 5, pin 122 rocks plate 103 about pin 107 as shown in Fig. 9. In doing so arm 109 and another arm 110 engage the trigger. The under side of trigger shoulder 111 is formed so as to provide a cam surface 111a against which arm 110 is adapted to abut when plate 103 is rotated to the position shown in Fig. 9 by the locking mechanism 115-117-119-122. In this position the operating end of the manually operated lever 99 is out of engagement with sliding plate 103 as shown in Fig. 9, thus preventing the outside operating mechanism from releasing trigger 45. The inside operating mechanism, however, through push button 57 and rod 63 connected to trigger 45 at 73, Fig. 9, can still rotate the trigger to release latch 39 and thus open the door. With arm 110 in sliding engagement with surface 111a rotation of the trigger in a releasing, or counterclockwise, direction will cause the plate member 103 to be moved back to its normal position, as shown in Figs. 7 and 8, in which lever 99 is again aligned with the notched portion of the plate whereby the outside operating mechanism is returned to an operative relationship with trigger 45.

Numerical 25 represents a safety catch slidable on pin 107 and biased to its Fig. 7 position by a second end of spring 51. Its end may extend through the wall of door casing 25 and ride over wedge 33 in the post member as the door moves toward its closed position. Before the latch and cam lock together the safety catch passes over the wedge and the door is held from accidental opening. This hold is released when the trigger end engages a part 127 of the safety catch and lifts it as will be seen by comparing Figs. 7 and 8.

Provision is also made to lock the door from release from within. For this purpose reciprocable rod 117 is provided with a lug 129. This lug 129 is keyed to rod 117 by means of a tongue 122a on the lug 129 working in a groove 129b in rod 117. Lug 129 rests on top of a fixed mounting element 130 provided with a lip 130a which overlies said lug 129. This rod 117 may be shifted up and down without movement of lug 129. However, by reason of the key connection the lug 129 may be moved from its full to its dotted line position (Fig. 6) by rotating rod 117.

Mounted on an offset portion of supporting element 130 is a U-shaped supporting bracket 130b having vertically aligned holes 130c formed in the legs thereof. Bracket 130b is adapted to support rod 117 for vertical and rotational movement.

When rod 117 is rotated on its axis, lug 129 is moved in a horizontal plane. This moves said lug 129 into the path of laterally disposed lug 131 on rockshaft 63. The lug 131, upon rotation of rockshaft 63, is moved in a vertical plane. If, as shown in Figs. 3 and 5, the lug 129 has been moved into the path of said lug 131, rotation of rockshaft 63 by push button 57 is prevented and release of trigger 45 is prevented.

If rod 117 is depressed only, the outside door handle is incapable of opening the door. If, however, said rod 117 is depressed and also rotated both the outside handle and the inside push button are prevented from releasing the trigger to open the door.

A lock on the outside of the door is marked 136. When the key is turned it rotates a stem and turns an inner arm 138. This arm engages a downturned arm 140 on plate 103 whereby the plate 103 is rotated precisely as it is rotated by the locking rods 115 and 117. When so rotated the handle 75 is prevented from rotating the locking trigger.

I claim:

1. In a door latch mechanism for use with a post member, having a keeper mounted on said post member and a door member having a cooperating latch mounted on said door member, means for releasing said latch from door locking position comprising, a substantially U-shaped handle adapted to be located outside of the door with its ends extending through the door, lever arms adapted to be terminally pivoted at opposite ends to and within the door and being connected at their other ends to the handle ends, whereby said handle is movable toward and away from said door, and means connecting said levers to said latch, for the purpose set forth.

2. In a door latch mechanism for use with a post member, having a keeper mounted on said post member and a door member having a cooperating latch mounted on said door member, means for releasing said latch from door locking position comprising, a substantially U-shaped handle adapted to be located outside of the door substantially parallel thereto with its ends extending through the door to the inside thereof, lever arms adapted to be terminally pivoted at opposite ends to and within the door and being connected at their other ends to the handle ends to mount the handle for movement toward and away from said door, and means connecting said levers to said latch, for the purpose set forth.

3. In a door latch mechanism for use with a post member, having a keeper mounted on said post member and a door member having a coop-

erating latch mounted on said door member, means for releasing said latch from door locking position comprising a substantially U-shaped member adapted to be located outside of the door with its ends slidably mounted in the door and extending to the inside thereof, a pair of pivotally interconnected levers adapted to be terminally pivoted at opposite ends to the inside of the door and being pivotally connected at their other ends to the handle ends whereby said handle is movable toward and away from said door.

4. In a door latch mechanism for use with a post member, having a keeper mounted on said post member and a door member having a cooperating latch mounted on said door member, means for releasing said latch from door locking position comprising, a substantially U-shaped handle adapted to be located outside of the door with its ends slidably mounted in the door and extending to the inside thereof, a pair of pivotally interconnected levers adapted to be terminally pivoted at opposite ends to the inside of the door and being pivotally connected at their other ends to the handle ends whereby said handle is movable toward and away from said door, and a spring acting on said levers to bias said handle toward said door.

5. In a door latching mechanism for use with a post member, having a keeper mounted on said post member and a door member having a cooperating latch mounted on said door member, means for releasing said latch from door locking position comprising, a substantially U-shaped handle adapted to be located outside of the door with its ends slidably mounted in the door and extending to the inside thereof, a pair of pivotally interconnected levers adapted to be terminally pivoted at opposite ends to the inside of the door and being pivotally connected at their other ends to the handle ends whereby said handle is movable rectilinearly toward and away from said door, a spring biasing said handle toward said door, and means connecting one of said levers to said latch, for the purpose set forth.

6. In a door latching mechanism for use with a post member, having a keeper mounted on said post member and a door member having a cooperating latch mounted on said door member, means for releasing said latch from door locking position comprising, a substantially U-shaped handle adapted to be located outside of the door with its ends slidably mounted in the door and extending to the inside thereof, a pair of pivotally interconnected levers adapted to be terminally pivoted at opposite ends to the inside of the door and being pivotally connected at their other ends to the handle ends whereby said handle is movable rectilinearly toward and away from said door, a spring acting on said levers to bias said handle toward said door and means connecting said levers to said latch, for the purpose set forth.

7. In a door latching mechanism for use with a door member and a post member having a keeper, and having a cooperating latch adapted to be mounted on said door member, and means for releasing said latch from door locking position comprising, a substantially U-shaped handle adapted to be located outside of the door with its ends slidably mounted in the door and extending to the inside thereof, a pair of pivotally interconnected levers adapted to be terminally pivoted at opposite ends to the inside of the door and being pivotally connected at their outer ends to the handle ends whereby said handle is movable rectilinearly toward and away from said door, a

spring acting on said levers to bias said handle toward said door, and an extension on one of said levers connected to said latch, for the purpose set forth.

5. In a door latch mechanism for use with a door member and a post member having a keeper mounted on said post member, a cooperating latch adapted to be mounted on said door member, trigger means to engage and hold said latch in door locking position, independent means for releasing said trigger means from the outside and from the inside of the door, a rod member mounted for reciprocable and rotatable movement, means connecting said rod member to said outside releasing means, means on said rod member engageable with said inside releasing means, said rod when reciprocated in one direction breaking said connecting means to said outside releasing means and when so reciprocated and also rotated being positioned to obstruct said inside releasing means.

9. In a door latch mechanism for use with a door and a post having a keeper member comprising a spring biased cam on said post, a cooperating spring biased pivoted latch member mounted in a casing carried on said door, a spring-pressed wedge in said post engaged by said casing in door closed position to urge said casing into contact with an adjacent portion of said post, and a safety catch in said door carried casing, said safety catch being biased toward said wedge and adapted to engage and be held by said wedge to prevent the door from opening before said latch and keeper fully engage, and trigger means engaging said safety catch and being engageable with said latch member, said trigger means being movable to retract said safety catch upon being disengaged from said latch member.

10. In a door latch mechanism, a spring actuated and pivoted latch member adapted resiliently to engage a keeper, trigger means adapted to engage said latch member and to hold said latch member from disengagement with said keeper, a spring actuated plate member movable to different positions and having a part extending upon one end of said trigger and adapted to engage said trigger for moving said trigger in one direction, said plate member having one position wherein said part engages said trigger, a first operating means for moving said plate member in one direction and into one of said different positions relative to said latch member, said first mentioned part of said plate member during movement of said plate by said operating means in said one direction being adapted to engage said trigger and to move said trigger from a position engaging to a position disengaging said latch member, a second operating means being adapted to move said plate to a second position in which said first operating means is operatively disconnected from said plate, a cam surface on said trigger, a second part projecting from said plate member and adapted to engage said cam surface when said plate is moved to the second position, a third operating means being adapted to move said trigger independently of said first operating means, said cam surface during the movement of the trigger by said third operating means being adapted to slidably engage said second plate part and to thereby return said plate to said first position.

11. In a door latch mechanism, a spring actuated and pivoted latch member adapted resilient-

ly to engage a keeper, trigger means adapted to engage said latch member and to hold said latch member from disengagement with said keeper, a spring actuated plate member movable to different positions and having a part extending upon one end of said trigger and adapted to engage said trigger for moving said trigger in one direction, said plate member having one position wherein said part engages said trigger and holds said trigger out of engagement with said latch member, a first operating means for moving said plate member in one direction and into one of said different positions relative to said latch member, said first mentioned part of said plate member during movement of said plate by said operating means in said one direction being adapted to engage said trigger and to move said trigger from a position engaging to a position disengaging said latch member, a second operating means being adapted to rotate said plate to a second position in which said first operating means is operatively disconnected from said plate, a cam surface on said trigger, a second part projecting from said plate member and adapted to engage said cam surface when said plate is rotated to the second position, a third operating means being adapted to move said trigger independently of said first operating means, said cam surface during the movement of the trigger by said third operating means being adapted to slidily engage said second plate part and to thereby return said plate to said first position.

12. In a door latch mechanism, a spring actuated and pivoted latch member resiliently to engage a keeper, trigger means adapted to engage said latch member and to hold said latch member from disengagement with said keeper, a spring actuated plate member having different positions and having a part extending beyond one end of said trigger and adapted to engage said trigger for moving the trigger in one direction, said plate member having a notch formed at one end thereof and having one position wherein said part engages said trigger and holds said trigger out of engagement with said latch member, a first operating means extending into the notch in said plate member and being adapted to engage said plate within said notch and to move said plate member into one of said different positions relative to said latch member, said first-mentioned part of said plate member during movement of said plate member in one direction by said first operating means being adapted to engage said trigger and to move said trigger from a position engaging to a position disengaging said latch, a second operating means associated with said plate member and being adapted to rotate said plate member out of engagement with said first operating means, a cam surface on said trigger, a second part projecting from said plate member and adapted to engage said cam surface when said plate is rotated out of engagement with said first operating means, and a third operating means being adapted to move said trigger independently of said first operating means, said cam surface during the movement of said trigger by said third operating means being adapted to slidily engage said second plate part and to thereby return said plate to said first position.

13. In a door latch mechanism, a spring actuated and pivoted latch member adapted to engage said latch member and to hold said latch member from disengagement with said keeper,

5 a spring actuated plate member movable to different positions and having a part extending upon one end of said trigger and adapted to engage said trigger for moving said trigger in one direction, said plate member having one position wherein said part engages said trigger and holds said trigger out of engagement with said latch member, a first operating means for moving said plate member in one direction and into one of said different positions relative to said latch member, said first mentioned part of said plate member during movement of said plate by said operator means in said one direction being adapted to engage said trigger and to move said trigger from a position engaging to a position disengaging said latch member, a second operating means being adapted to move said plate to a second position in which said first operating means is operatively disconnected from said plate, a cam surface on said trigger, a second part projecting from said plate member and adapted to engage said cam surface when said plate is moved to the second position, a third operating means being adapted to move said trigger independently of said first operating means, said cam surface during the movement of the trigger by said third operating means being adapted to slidily engage said second plate part and to thereby return said plate to said first position, said second operating means including a blocker member, said blocker member being positionable with said plate in said second position to restrain said third operating means against movement.

35 14. In a door latch mechanism of the type having a latch adapted to engage a keeper to prevent the opening of the door, a trigger engaging said latch to retain said latch in engagement with said keeper, means operatively connected to said trigger to move said trigger out of engagement with said latch from inside said door, and another means operatively connected to said trigger to move said trigger out of engagement with said latch from outside said door and a locking device on one side of said door for preventing movement of said trigger, in which said locking device is movable to a plurality of locking positions, said locking device including a linkage assembly operatively connected to one of said trigger moving means, said assembly being adapted to operatively disconnect the associated trigger moving means from said trigger, and an element being adapted to restrain said other trigger operating means against movement, said linkage assembly being rendered operative in one of said locking positions and both said linkage assembly and said element being rendered operative in another of said locking positions.

40 15. In a door latch mechanism of the type having a latch adapted to engage a keeper to prevent the opening of the door, a trigger engaging said latch to retain said latch in engagement with said keeper, means operatively connected to said trigger to move said trigger out of engagement with said latch from inside said door, and other means operatively connected to said trigger to move said trigger out of engagement with said latch from outside said door and a locking device on the inside of said door for preventing movement of said trigger, in which said locking device is movable axially or axially and rotationally to a plurality of locking positions, said locking device including a linkage assembly operatively connected to one of said trigger moving means, said assembly being adapted to op-

eratively disconnect the associated trigger moving means from said trigger, and an element being adapted to restrain said other trigger operating means against movement, said linkage assembly being rendered operative in moving said device axially and both said linkage assembly and said element being rendered operative in moving said locking device axially and rotationally.

16. In a door latch mechanism of the type having a latch adapted to engage a keeper to prevent the opening of the door, a trigger engaging said latch to retain said latch in engagement with said keeper, means operatively connected to said trigger to move said trigger out of engagement with said latch from inside said door, and other means operatively connected to said trigger to move said trigger out of engagement with said latch from outside said door and a locking device on one side of said door for preventing movement of said trigger, in which said locking device is movable to a plurality of locking positions, said locking device including a rod member axially movable to one of said positions and axially and rotationally movable to another locking position, a linkage assembly operatively connecting one end of said rod to one of said trigger moving means, said assembly being adapted to operatively disconnect the associated trigger moving means from said trigger upon the axial movement of said rod, and an element mounted upon said rod and adapted to restrain said other trigger operating means against movement upon both the axial and rotational movement of said rod.

17. In a door latch mechanism of the type having a latch adapted to engage a keeper to prevent the opening of the door, a trigger engaging said latch to retain said latch in engagement with said keeper, means operatively connected

to said trigger to move said trigger out of engagement with said latch from inside said door, and other means operatively connected to said trigger to move said trigger out of engagement with said latch from outside said door and a locking device on one side of said door for preventing movement of said trigger, in which said locking device is movable to a plurality of locking positions, said locking device including a rod member axially movable to one of said positions and axially and rotationally movable to another of said locking positions, a linkage assembly operatively connecting said rod to said outside trigger moving means, said assembly being adapted to operatively disconnect the outside trigger moving means from said trigger upon the axial movement of said rod, and an element mounted upon said rod and adapted to restrain said inside trigger operating means against movement upon both the axial and rotational movement of said rod.
